UNITED STATES PATENT OFFICE.

FRANCIS H. WITTSTEIN, OF NEWARK, NEW JERSEY.

DESIGN FOR A FINGER-RING.

58,980.

Specification for Design.

Patented Sept. 6, 1921.

Application filed January 6, 1921. Serial No. 435,523. Term of patent 7 years.

To all whom it may concern:

Be it known that I, FRANCIS H. WITTSTEIN, a citizen of the United States, residing at Newark, in the county of Essex and State of New Jersey, have invented a new, original, and ornamental Design for Finger-Rings, of which the following is a specification, reference being had to the accompanying drawing, forming part thereof.

Figure 1 is an edge elevation of a finger ring embodying my new design;
Fig. 2 is a side elevation thereof, and
Fig. 3 is a transverse sectional view of the ring as illustrated in Fig. 2.

I claim:

The ornamental design for a finger ring, as shown.

FRANCIS H. WITTSTEIN.
